UNITED STATES PATENT OFFICE.

SEBASTIAN GAUL, OF HOBOKEN, NEW JERSEY.

SPITTOON-HOLDER.

1,318,660.

Specification of Letters Patent. Patented Oct. 14, 1919.

Application filed March 24, 1919. Serial No. 284,726.

To all whom it may concern:

Be it known that I, SEBASTIAN GAUL, a citizen of Germany, and resident of Hoboken, in the county of Hudson and State of New Jersey, have invented certain new and useful Improvements in Spittoon-Holders, of which the following is a full, clear, and exact specification.

This invention relates to holders or supports for spittoons or cuspidors, and has for its object to provide supporting means which may be attached to a bed or other piece of furniture so as to normally support the spittoon out of the way, and having improved and simplified means for bringing the spittoon into position for use when desired and for automatically returning said spittoon to normal retracted position as soon as the operating means is released. Other objects will appear as the description proceeds.

The invention will be first hereinafter described in connection with the accompanying drawings, which constitute part of this specification, and then more specifically defined in the claims at the end of the description.

In the accompanying drawings wherein similar reference characters are used to designate corresponding parts throughout the several views:

Figure 1 is a side elevation of a portion of a bed showing the spittoon holder attached to one of the side rails thereof.

Fig. 2 is a plan view of the parts shown in Fig. 1, the spittoon being in normal position under the bed.

Fig. 3 is a plan view of the holder on a larger scale.

Fig. 4 is a side elevation of the holder in retracted position, the side rail of the bed to which said holder is secured being shown in section.

Fig. 5 is a similar view showing the holder in projected position, and

Fig. 6 is a section on the line VI—VI of Fig. 4.

In Figs. 1 and 2 of the drawings, 1 designates the head piece of a bed of common construction, and 2 indicates one of the side rails here shown as of angle iron but which may be of any other shape. As shown, the bracket 4 of the spittoon holder is clamped to the horizontal flange 3 of the side rail 2 by means of a pair of jaws 5 embracing said flange and one or more set screws 9

mounted on one of said jaws and engaging one face of the flange while the other face is engaged by the other jaw. The two jaws may be fastened together by rivets 8.

An arm 6 is pivotally mounted on the bracket 4 by means of a pintle bolt 13 passed vertically through upper and lower flanges 10 on said bracket, and through the hub 12 at one end of the arm. The flanges 10 are connected together by a vertical portion 11 of the bracket which is arranged adjacent the hub 12. The bolt 13 may be held in place by nuts 14 on its upper and lower ends, or otherwise. Said hub carries a worm 15 which is engaged on opposite sides by rollers 20 carried by a lever 16 which is pivoted to an extension 19 of the vertical portion 11 of the bracket at 18 and is adapted to swing up and down against the face of said vertical part 11 with the rollers always in engagement with said worm. The lever 16 is normally retained in its upwardly swung position, as illustrated in Figs. 1, 2, 3, 4 and 6, so as to hold the arm 6 in retracted position, by a spring 21 connected at its upper end, as at 22, to the upper flange 10 of the bracket, and having its other end connected to the lever at 23, Fig. 6. The free end of the lever may be equipped with a finger piece 17 which normally protrudes slightly beyond the side rail 2 of the bed. By pressing down on the finger piece 17, the lever may be moved to the position shown in Fig. 6, and during this movement the rollers 20 will in conjunction with the worm cause the arm 6 to swing out beyond the side rail of the bed. This downward movement of the lever 16 expands the coiled spring 21 and places the same under tension which acts to automatically return the lever and arm to normal positions as soon as the pressure on the finger piece is removed.

To prevent the arm 6 from returning to normal position under the influence of the spring with a jar and unpleasant noise, cushioning means are provided in the form of a leaf spring 24 secured to the lower flange 10 of the bracket and over which the lower edge of the arm rides as it returns to normal position. The extremity of said leaf spring is curved to guide the edge of the arm up over it, and near its inner end said spring has a hump or abutment 25 formed therein to gradually bring the arm to rest.

A spittoon 7 may be secured in any suit-

able manner to the free end of the arm 6. As here shown, the arm may have a vertical loop 26 engaging a vertical strip 27 fastened to the body and rim of the spittoon.

5. Having thus described my invention, what I claim as new and desire to secure by Letters Patent of the the United States is:—

10. 1. The combination with a bracket to be secured to a piece of furniture, of an arm pivoted on said bracket and adapted to support a spittoon, said arm being adapted to swing on said bracket but retained against axial movement thereon, a worm on said arm concentric with the pivotal axis there-

15. of, and means carried by the bracket for engaging the worm and swinging the arm.

20. 2. The combination with a bracket to be secured to a piece of furniture, of an arm having a hub pivoted on said bracket but retained against axial movement thereon, a worm on said hub of the arm, a lever pivoted on the bracket, and means on the lever to engage the worm for swinging said arm when the lever is actuated.

25. 3. The combination with a bracket to be secured to a piece of furniture, of an arm having a hub pivoted on the bracket but retained against axial movement thereon, a worm on said hub, a lever also pivoted on the bracket, means on the lever to engage the worm for swinging said arm when the lever is actuated, and means for automatically returning the arm and lever to normal position when the latter is released.

30. 35. 4. The combination with a bracket, of an arm having a hub pivoted on the bracket, a worm on said hub, a lever also pivoted on

the bracket, and spaced pins on the lever to engage opposite faces of the worm for swinging the arm when the lever is actuated. 40

5. The combination with a bracket, of an arm having a hub pivoted on said bracket, a worm on said hub, a lever also pivoted on the bracket, spaced pins on the lever to engage opposite faces of the worm for swinging the arm when the lever is actuated, and a spring connected to the bracket and lever for automatically returning the arm and lever to normal position when the latter is 45 released. 50

6. The combination with a bracket, of an arm having a hub pivoted on said bracket, a worm on said hub, a lever also pivoted on the bracket, spaced pins on the lever, and rollers on said pins to engage the opposite faces of the worm for swinging the arm when the lever is actuated. 55

7. The combination with a bracket having parallel flanges, of an arm mounted to swing on the bracket between said flanges and retained against axial movement thereby, means for swinging the arm, means for automatically returning the arm to normal position when the actuating means is released, 60 and a leaf spring mounted on one of said flanges and having an inclined portion over which said arm rides in returning to normal position and which serves to retard and cushion said return movement of the arm. 65 70

In testimony whereof I have signed my name to this specification.

SEBASTIAN GAUL.
